UNITED STATES PATENT OFFICE.

WILLIAM L. CHURCH, OF NEWTON, MASSACHUSETTS, ASSIGNOR TO THE UNI-FORM COMPANY, OF BOSTON, MASSACHUSETTS, A CORPORATION OF MASSACHUSETTS.

APPARATUS FOR CONSTRUCTING CONCRETE FLOORS AND WALLS.

1,293,036.

Specification of Letters Patent. Patented Feb. 4, 1919.

Application filed June 27, 1918. Serial No. 242,321.

To all whom it may concern:

Be it known that I, WILLIAM L. CHURCH, a citizen of the United States, and a resident of Newton, in the county of Middlesex and 5 State of Massachusetts, have invented a new and useful Improvement in Apparatus for Constructing Concrete Floors and Walls, of which the following is a specification.

My invention relates to apparatus for 10 constructing concrete floors and walls and its objects are to improve and simplify the same in the manner hereinafter set forth.

Apparatus of the general type described herein has been set forth in detail in the application of N. F. Amburseen, Serial No. 229,168, filed April 17, 1918, and the claims of the present case are directed to certain modifications thereof in the nature of simplifications and improvements.

20 In the drawings which accompany and form a part of this specification—

Figure 1 is a horizontal section of my improved apparatus showing the use thereof for constructing a single-rib wall. Fig. 25 2 is a vertical section showing the arrangement of my apparatus for molding a reinforced concrete floor having reinforced concrete ribs formed integral therewith. Fig. 3 is a vertical section showing said apparatus arranged for constructing a flat slab floor. Fig. 4 is a fragmentary sectional view showing in a somewhat exaggerated manner the use of the gap-stopping member hereinafter described between a form and channel. Fig. 5 is an end view 30 on an enlarged scale of said gap-stopping member. Fig. 6 is a similar view of another form of gap-stopping member. Fig. 7 is a vertical section taken on the line 7—7 40 of Fig. 4 and showing the use of said gap-stopping member between two adjacent forms. Fig. 8 is a perspective view of a detail of construction.

In the particular drawings selected for 45 more fully disclosing my invention, 1, 1 represent support members for the metallic forms 2, 2, said support members being shown in the present instance as metallic channels. In constructing a wall the channels are arranged vertically and are spaced 50 apart, a form 2 being arranged between each pair of adjacent channels. The forms are provided with plane surfaces and their ends terminate in flanges 3 each of which

makes an acute angle with said surface, said 55 flanges acting as stiffening members. The sides 4 of the forms are formed integral therewith and each takes an acute angle with the plane surface thereof, said sides terminating in inwardly extending flanges 60 5 which are substantially parallel with said surface.

In order to prevent the forms from moving outwardly with respect to the channels in wall construction, I have shown in the 65 present instance buttons 6, preferably light channels, which are apertured to receive the headed bolts 7 passing through the web of each channel 1 and which extend beyond the latter and abut the flanges 5 aforesaid 70 of the side members of the forms, a wing nut 8 being threaded to the outer end of said bolt to hold said buttons in position. In order to prevent the forms from moving inwardly before the concrete is poured, I 75 provide a clip 9 arranged to take over the inwardly extending flanges 5 of the forms and rest against the outer surface of the webs of the channels.

As shown in Fig. 2 the laterally-spaced, 80 channels are supported on suitable false work indicated at 10 and transverse and longitudinal reinforcing members 11 and 12 are suitably supported in the slab portion and in the ribs of the floor respectively. 85 In Fig. 3 the longitudinal reinforcing members are indicated at 13.

It has been found that the sheet-metal forms 2 become somewhat battered in use and do not always make tight joints with 90 each other or with the channels. To overcome this defect I provide a gap-stopping member consisting, as shown in Fig. 5 at about twice its actual size, of a thin sheet of metal reversely bent to form a body portion 14, the upper ends of each half of which terminate preferably in the cap portions 15, 15 which may be slightly curved as indicated to prevent their extremities from being forced out of contact with the forms and 100 channels with which they are in contact. The body portion is adapted to fit into any gap that may be left between the concrete forms and the channels as shown in Fig. 4, or between two contiguous forms as 105 shown in Fig. 7, the elasticity of the material of which it is made insuring a tight fit. The cap members rest respectively on

the forms and channels, or on two contiguous forms, and insure practically waterproof joints.

5 In Fig. 6 the body portion 16 of the gap-stopping member consists of a single piece provided at its upper end with curved cap members 15', 15'.

10 It will be understood however that the gap-stopping members need not be made of metal and that paper or any other suitable material may be used for this purpose.

15 It is highly desirable in floor construction that the flanges 3 and the side members 4 of the forms should each make an acute angle with the surface of the form so that each side member will be angularly arranged with respect to the flange of its contiguous channel and each end flange 3 will make an angle with the flange of its contiguous form, 20 so that spaces progressively increasing in width downwardly will be formed. The surface of each plane form is flush with one of the surfaces of the channels, either the surface of the inner ends of the flanges or. 25 the outer surface of the web, and the sides of the forms make contact with the flanges at the upper portion thereof, as clearly shown in Figs. 2 and 3. If the joint is not watertight a certain amount of seepage will 30 occur and unless the parts are designed to prevent the cement mortar from collecting in the space between the sides and the flanges of the channels or between the end flanges 3 of two adjacent forms, a bond will 35 be formed between these members which will increase the difficulty of removing the forms after the concrete has hardened. By arranging the sides and flanges of the forms angularly in the manner above set forth all 40 danger of the formation of such bond is eliminated.

Having thus described illustrative embodiments of my invention without however limiting the same thereto what I claim and desire to secure by Letters Patent is:

45 1. In an apparatus for constructing concrete floors and walls, a form having a plane surface, end flanges integral therewith, and sides each making an acute angle with said surface.

50 2. In an apparatus for constructing concrete floors and walls, a form having a plane surface, end flanges and sides, said flanges and sides each making an acute angle with said surface.

55 3. In an apparatus for constructing concrete floors and walls, a form having a plane surface, and sides each making an acute angle with said surface, said sides terminating in inwardly-extending flanges substantially parallel with said plane surface.

60 4. In an apparatus for constructing con-

crete floors, laterally-spaced channels, plane forms arranged between each pair of adjacent channels, said forms each having the 65 upper portion of its sides in contact with said channels, the surface of each of said forms being flush with one of the surfaces of the contiguous channels and the sides thereof being arranged angularly with respect to said flanges whereby a space progressively increasing in width downwardly 70 is formed between each said side and the flange of the contiguous channel.

75 5. In an apparatus for constructing concrete floors, laterally-spaced channels, plane forms arranged between each pair of adjacent channels, said forms each having the upper portion of its ends in contact with the adjacent forms, the surface of each form 80 being flush with the surface of the adjacent forms and the ends thereof being arranged angularly with respect to said surface whereby a space progressively increasing in width downwardly 85 is formed between each pair of adjacent ends.

90 6. In an apparatus for constructing walls, laterally-spaced channels, plane forms placed between each pair of adjacent channels, means for preventing said forms from moving outwardly with respect to said channels, and one-piece, detachable clips each arranged to fit over a portion of a form and to coöperate with said channels for preventing said forms from moving inwardly. 95

7. In an apparatus for constructing concrete floors, laterally spaced channels, plane forms placed between each pair of adjacent channels and abutting the flanges of the same and flexible means for bridging the 100 gap between each form and its adjacent channel.

8. Apparatus for constructing concrete floors comprising laterally-spaced channels, plane forms placed between each pair of adjacent channels and abutting the flanges of the same, and gap-stopping members each having a body portion arranged to fit into the gap between each form and its adjacent channel and a two-part cap resting on said 110 form and channel.

9. Apparatus for constructing concrete floors comprising laterally-spaced channels, plane forms placed between each pair of adjacent channels and abutting the flanges of the same, and gap-stopping members each having a body portion arranged to fit into the gap between each pair of adjacent forms and a two-part cap resting on the surface of said forms. 115

120 In testimony whereof, I have hereunto subscribed my name this 11th day of June, 1918.

WILLIAM L. CHURCH.
